Dec. 1291

David Hathaway, of Troy, N.Y.
Assignor to Fuller, Warren & Co., of same place.
Letters Patent No. 1291, dated July 31, 1860.

The schedule referred to in these Letters Patent and making part of the same,

To all whom it may concern:

Be it Known that I, David Hathaway, of the City of Troy, in the County of Rensselaer, and State of New York, have invented a new and original design for Coal-Stove plates: - and I do hereby declare that the following is a full, and exact description of the same, reference being had to the annexed photographic drawings which make a part of this Specification and in which

Fig: 1. is a perspective view indicating the general form,

Fig: 2. a plan of the hearth plate, A.

Fig: 3. a plan of the top plate B. of the base,

the base: Fig: 4. an elevation of the front plate, C, and a corner plate, D,

Fig: 5. an elevation of a side-plate E, of the base, and

Fig: 6. a plan of the uppermost top plate, F, all of a Stove bearing or having my said new design: -

In this design the Stove-plates are shaped and ornamented as follows, to wit: - the hearth plate, A, is of the form represented in Fig: 2, and has the punctured moulding, Z, and the crimped moulding, Y, arranged upon it as shown in that drawing. The top plate B, of the base of the Stove has the form shown by Fig: 3, and is ornamented by the crimped border moulding, X, and has the octagonal, scalloped mould-

ing, w, surrounding the eight inclined panels which are terminated on their inner upper sides by an arc of a circle and are ornamented by the arch like pendants, v, all formed and arranged as represented in Fig: 3.

The front plate, c, of the base of the stove is ornamented with the compound, scalloped, and crimped moulding, u, arranged so as to form an oblong rectangular panel within it, as shown in Fig: 4. Each of the four corner plates, D, (only one shown) of the base, is of a concave form and is ornamented with the figures s. and r. shaped and arranged together upon the plate as represented in Fig: 4. Each side plate, B, of the base is ornamented with a bead like moulding, q, and scalloped and punctured moulding p, shaped and arranged together and upon the plate as shown in Fig: 5.

And the top plate, I, of the stove is of the usual form shown in Fig: 6. and has the concentric ornamental ledges, o, and m, and the mouldings n, l, and k, formed and arranged as represented in Fig: 6.

What I claim as my invention or production and desire to secure by Letters Patent is the ornamental design of Stove Plates herein described and represented in the annexed drawings

Witness

Edw. Thos. J. Cornelius,
G. M. Austin & Park.
